CLAIM

The ornamental design for a scented jar, as shown and described.

DESCRIPTION

FIG. 1 is a perspective view of a scented jar;

FIG. 2 is a side view thereof, the front, back and other side views being identical;

FIG. 3 is a top view thereof;

FIG. 4 is a bottom view thereof;

FIG. 5 is a perspective view of the scented jar in an opened configuration; and,

FIG. 6 is a side view thereof, the front, back and other side views being identical.

The broken lines illustrate portions of the scented jar that form no part of the claimed design.

1 Claim, 6 Drawing Sheets(56)
